UNITED STATES PATENT OFFICE

AUGUST FRISCH, OF REBSTEIN, ST. GALLEN, SWITZERLAND

LUBRICANT AND FUEL PUMP

Application filed December 9, 1927, Serial No. 238,848, and in Switzerland February 12, 1927.

The present invention relates to a pump which is adapted to convey lubricant to a bearing or fuel into a cylinder.

The invention relates particularly to pumps 5 of the type in which a reciprocating piston is provided in a cylinder, which latter cooperates with suction and ejection openings.

The object of the invention is to provide 10 an improved pump which independently of the viscosity of the liquid delivers a predetermined quantity of liquid at a high adjustable pressure. A further object consists in making the quantity delivered always accurately in accordance with the number of 15 strokes of the piston.

A still further object is to provide a pump 20 which delivers a predetermined quantity of liquid at a high adjustable pressure independently of the direction of rotation of the driving shaft of the pump.

With the above and other objects in view the invention resides in certain novel features of construction and in the combination and arrangement of parts as hereinafter more 25 fully described.

In the drawing:

Fig. 1 shows a cross section of the pump mounted in an oil reservoir.

Fig. 2 is an axial section.

Fig. 3 shows a cross section of the pump 30 whilst delivering oil.

Fig. 4 shows a cross section of the pump and shows the driving members.

Fig. 5 is a side elevation of the pump, some 35 of the parts being in section.

The pump illustrated is provided with ring elements 29, each of which is provided with a pump and which, together with two cap-shaped ends form a closed oil supply tank.

40 In the ends is mounted a shaft 1 serving to drive the pumps of all the elements and which may be driven by a worm and worm wheel (Figs. 4 and 5).

On the driving shaft 1 there is mounted 45 for each pump a lifting eccentric 9 and on this is rotatably mounted a driving disc 11. When rotated the driving disc 11 moves a

driving frame 3 guided in a straight line in stationary guides 18, 19 of the element 29.

50 A resilient member (spring) 2 connects the

frame 3 to the pump cylinder 4. The latter is provided with a suction valve extension 5 which, together with a stationary seat 6 in the ring 29, forms an inlet valve. The driving disc 11 mounted adjacent the eccentric 9 and loosely rotatable thereon is driven by the pin 12 of the eccentric 9, engaging with a groove 13 of the disc 11. The eccentric 9 raises and lowers the frame 7 guided in the guides 18, 19 and carrying the piston 8. The latter operates in the cylinder 4 actuated by the disc 11. Into the frame 7 is screwed a lifting screw 10 having a square portion 14 slidably seated in a square opening of an adjusting sleeve 15 with head 16. This is loosely rotatable on an extension of the pump casing 29 provided with a scale 17. The seat 6 is provided on a casing 20, rigidly mounted in the pump casing 29, and provided with a seat for a non-return conical valve 21. To the casing 29 is connected the pressure pipe 27 by which the oil can be conducted to the point of use.

The method of operation is as follows:

Having reached the lower dead point position Fig. 1, the hump 22 of the driving disc 11 pushes the cylinder 4 downwards and opens a comparatively very large annular section of the suction valve 6, 5 for the whole duration of the suction stroke of the piston 8. The liquid is drawn in in the direction of the arrow. On completion of the suction stroke the hump 22 on the driving disc 11 presses the driving frame 3 with the cylinder 4 upwardly, closes the suction port at 5, 5, the piston 8 is moved downwardly by the eccentric 9 and the liquid is forced through the valve 21 into the pipe 27 to the point where the liquid is to be used. The screw 10 is adjusted by adjustment against the scale 17 and more or less play is given to the eccentric 9 in the cross head 7 so that the maximum piston stroke is reduced by the amount of play.

The cylinder control continues to operate irrespective of the stroke adjustment of the piston and thus ensures the supply of the adjusted quantity. In order that the suction valve seat 5, 6 may still be pressed up even in the case of wear of the actuating cam

the resilient member 2 (blade spring) is interposed between the actuating frame 3 and the pump cylinder 4. If the direction of the pump shaft changes then the driving pin 12 travels idly through the circular groove for about 180° and again drives the driving disc 11 when the actuating position for the opposite direction of rotation is obtained.

The construction illustrated is particularly designed for use as a unit in the type of pumping apparatus disclosed and claimed in my copending application, Serial No. 176,393, filed Mar. 18, 1927.

While the preferred embodiment of the invention has been described I do not wish to be limited to the particular construction set forth, as minor changes in detail may be resorted to within the scope of the following claims.

20. What I claim is:—

1. An improved lubricant and fuel pump comprising a cylinder mounted so as to be axially movable, a piston working in said cylinder, a suction passage connected to said cylinder, a closure member included in said suction passage, said closure member being capable of being opened and closed by said cylinder, a driving shaft, a resilient member between the driving shaft and the cylinder, and a pressure passage co-operating with said cylinder.

2. A pump comprising a movably mounted cylinder, a piston in said cylinder, means for positively actuating said cylinder and for imparting a reciprocating movement to said piston, conduits for conducting liquid into and from said cylinder, said cylinder being itself constructed as a valve body for co-operating with said conduits, and means for varying the stroke of said piston, said means comprising a stroke limiting screw disposed in the direction of the piston movement and seated in the piston guiding frame, said screw having a square portion, and a rotatably mounted sleeve seated on said square portion.

3. An improved lubricant and fuel pump comprising a movably mounted positively actuated cylinder, a piston in said cylinder, a driving shaft, an eccentric on said shaft, a driving disc rotatably mounted on the eccentric, a driving member on the eccentric, said driving disc being loosely mounted on the hub of the eccentric, said eccentric having a semicircular slot with which the driving member engages in such a manner that when changing the direction of rotation the control will be such as to correspond to the reversed direction of rotation, and conduits for conducting liquid into and from the cylinder, said cylinder serving as the closure member for said conduits.

4. A pump including a drive shaft, an axially movable cylinder, an axially movable piston therein, an eccentric on said shaft for reciprocating said piston, a disc driven by

said shaft for reciprocating said cylinder, said disc having lost motion connections to said shaft permitting relative movement through approximately 180°, whereby the predetermined sequence of movement of the piston and cylinder may be maintained upon reverse rotation of said shaft, and means for controlling the admission of fluid to and from said cylinder.

5. A pump including a supply chamber having an outlet conduit, a cylinder movable axially and having a part serving as a valve to control the admission to the cylinder of fluid from said chamber, a shaft disposed within said chamber, a member on said shaft for reciprocating said cylinder, a piston within said cylinder, and a member on said shaft for reciprocating said piston, one of said members being relatively rotatable in respect to said shaft and through a limited distance, whereby operation of said pump may be effected upon rotation of said shaft in either direction.

6. A pump including a supply chamber having a compartment at the lower part thereof, a delivery conduit connected to said compartment, a cylinder within said chamber and having a part thereof serving as a valve to control communication between said chamber and said compartment, a piston within said cylinder, a drive shaft within said chamber, an eccentric on said shaft for reciprocating said piston, means exterior to the compartment for adjusting and controlling the stroke of the piston, and means driven by said shaft for reciprocating said cylinder to operate said valve part.

7. A pump including a supply chamber having a substantially cylindrical wall, a shaft projecting axially through said chamber, an outlet conduit connected to said wall, a cylinder projecting substantially radially within said chamber and movable in the direction of its own axis, a spring pressed valve controlling communication between said cylinder and said conduit, means permitting admission of liquid to said cylinder from said chamber when said cylinder is moved axially to a predetermined position, a piston within said cylinder, and means for reciprocating said piston and said cylinder upon rotation of said shaft.

8. A pump including a supply chamber, a cylinder disposed therein and axially movable to control communication between the chamber and the cylinder, a piston within said cylinder, a spring for normally holding said cylinder in position to prevent said communication, means for reciprocating said piston, and means for moving said cylinder against the action of said spring to open said communication during the suction stroke of said piston.

9. A pump including an axially movable cylinder, a drive shaft, means for supplying

fluid to said chamber when the latter is in a predetermined position, means for reciprocating said cylinder, an eccentric connected to said last mentioned means, a frame connected to said piston and encircling said eccentric, and means for varying the lost motion between said frame and said eccentric to control the length of stroke of said piston.

10. A pump including a supply chamber having a cylindrical peripheral wall, a cylinder mounted to reciprocate substantially radially of said chamber and disposed therein and having a part serving as a valve to control communication between said cylinder and said chamber, a delivery conduit connected to said wall, a valve controlling communication between said cylinder and said conduit, a pair of reciprocatory members, a piston within said cylinder, a pair of reciprocatory parts within said chamber, one connected to said piston and the other having yielding connection to said cylinder, and a shaft having means for effecting reciprocation of said members.

25. 11. A pump including a supply chamber having a cylindrical peripheral wall, a cylinder mounted to reciprocate substantially radially of said chamber and disposed therein and having a part serving as a valve to control communication between said cylinder and said chamber, a delivery conduit connected to said wall, a valve controlling communication between said cylinder and said conduit, a pair of reciprocatory members, a bracket 30 projecting inwardly from said wall, reciprocatory members guided by said bracket, one being connected to said piston and the other to said cylinder, a shaft for effecting reciprocation of said members, and means carried by 35 said cylindrical wall for varying the stroke of said piston.

In testimony whereof I affix my signature.
AUGUST FRISCH.
